UNITED STATES PATENT OFFICE.

ALFRED F. MACRINI, OF NEW YORK, N. Y.

FIREMAN'S MASK.

1,079,251.

Specification of Letters Patent.

Patented Nov. 18, 1913.

Application filed May 10, 1912. Serial No. 696,538.

To all whom it may concern:

Be it known that I, ALFRED F. MACRINI, a citizen of the United States, residing at New York, in the county of New York and State 5 of New York, have invented new and useful Improvements in Firemen's Masks, of which the following is a specification.

This invention relates to masks and more particularly to firemen's masks.

10 The object of the invention is to provide a simple and efficient apparatus or device of this character which, when securely fastened upon the head of the wearer, will permit with perfect safety, the wearer to enter 15 rooms or other places wherein the air is surcharged with gases, vapors, or the like.

A further object of the invention is to obviate the difficulties heretofore encountered in devices of this character, that of maintaining the eye piece glass perfectly clear at all times so that condensation of the wearer's breath or outside vapors may be readily removed from the eye piece glass without removal of the mask.

25 A further object of the invention is the provision of a novel eye piece having a lid hinged thereto whereby the same may be opened so that the operator can secure fresh air without removing the mask.

30 A still further object of the invention is the provision of a novel respirator box adapted to contain air filtering members in such a manner that they may be readily removed when necessary.

35 A still further object of the invention is the provision of a device of this character carrying a self containing light which will not ignite explosive gases.

Further objects of this invention will appear as the following specific description is read in connection with the accompanying drawing, which forms a part of this application, and in which:

Figure 1 is a perspective view of the device shown applied. Fig. 2 is a vertical sectional view therethrough. Fig. 3 is a top plan view. Fig. 4 is a horizontal section taken on the line 4-4 of Fig. 2. Fig. 5 is a detail vertical sectional view through the 50 respirator box. Fig. 6 is a horizontal sectional view taken therethrough. Fig. 7 is

an enlarged vertical sectional view through the cover and lining. Fig. 8 is a detail perspective view of one of the cleaner pad clamps. Fig. 9 is a perspective view of the 55 lamp holding bracket. Fig. 10 is a detail perspective view of the buckle.

Referring more particularly to the drawing, 1 represents a mask or casing which is preferably formed of flexible leather and is 60 adapted to cover the top of the wearer's head, extend over the face and under the chin, as shown in Fig. 1. The device is held in place by a suitable buckle strap 2 which extends back of the wearer's neck and which 65 is adapted to firmly hold the device in place. In the front of the casing the mask is provided with a pair of openings 3 and 4, the former arranged in line with the wearer's eyes and the latter in line with the nose or 70 mouth.

Closing the opening 3 is a casing 3' which is flanged as shown at 5, to receive the securing screws or bolts 6 which pass through the flanges and through the edges of the 75 leather and are entered into flexible retaining strips 7, as shown in Figs. 2 and 4, the heads being covered by a flexible pad or cushioning strip 8. The casing 3' has hinged to one side thereof a lid 9 which is provided with separate pairs of outstanding lugs 10 80 at its free edge which are adapted to be engaged by the pivoted bolts 11 carried by the casing 3'. These bolts are provided with the usual wing nuts for clamping the bolts 85 upon the lugs. The lid is provided with a central opening which is closed by a glass 12 held in between separate gaskets 13 and 14, the former bearing against the outer edge of the casing 3'.

In order to keep the outer face of the glass 12 clear there is secured to the lid in any suitable manner, a pair of parallel rods 15, upon which are slidably mounted the mounting sleeves 16. These sleeves carry a rubber 95 member 17 in which is secured a felt pad or rubber 18 and which is provided with an operating handle 19, as shown, so that the same may be moved over the glass. It will be noticed that the sleeves 16 are enlarged 100 at their ends, as shown at 20, so as to prevent disengagement of the rubber member

of the wearer, and means to constrict said packing ring.

5. A mask of the character described comprising a hood, means to secure the same upon the head of the wearer, a packing ring arranged inside the hood and adapted to surround the face of the wearer, said packing ring being constructed of natural wool,

and a spring embedded in the packing ring for constricting the same.

In testimony whereof I affix my signature 10
in presence of two witnesses.

ALFRED F. MACRINI.
